(57) **CLAIM**

I claim the ornamental design for a double-ended sports paddle, as shown and described.

DESCRIPTION

FIG. 1 is a perspective view of a double-ended sports paddle, showing my new design;

FIG. 2 is a partial, enlarged perspective view thereof, taken along line 2 of FIG. 1;

FIG. 3 is a partial, enlarged perspective view thereof, taken along line 3 of FIG. 1;

FIG. 4 is a partial, enlarged perspective view thereof, taken along line 4 of FIG. 1;

FIG. 5 is a front elevational view of FIG. 1;

FIG. 6 is a rear elevational view of FIG. 1;

FIG. 7 is a top plan view of FIG. 1;

FIG. 8 is a bottom plan view of FIG. 1;

FIG. 9 is an enlarged left-side elevational view of FIG. 1; and,

FIG. 10 is an enlarged right-side elevational view of FIG. 1. The broken lines showing text in FIGS. 1-8 depict environmental matter and form no part of the claimed design.

1 Claim, 6 Drawing Sheets
